CLAIM

The ornamental design for an accessory for mobile phone case, as shown and described.

DESCRIPTION

FIG. 1 is a right front perspective view of an embodiment of an accessory for mobile phone case embodying the new design in a closed configuration.

FIG. 2 is a left rear perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof.

FIG. 8 is a bottom plan view thereof.

FIG. 9 is a right front perspective view of an accessory for mobile phone case according to FIG. 1 in an open configuration.

FIG. 10 is a left rear perspective view thereof.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan view thereof; and,

FIG. 16 is a bottom plan view thereof.

The broken lines in the drawings illustrate portions of the accessory for mobile phone case that form no part of the claimed design.
